Samuel B. Newell, of Cincinnati, Ohio.
 Letters Patent No. 1889-Dated Jan. 26, 1864.
 Design for a Trade-mark.

The schedule referred to in these Letters Patent and making part of the sa

 To all whom it may concern:

Be it known that I, Samuel B. Newell, of Cincinnati, in the County of Hamilton and State of Ohio, have invented a certain new print or picture to be used as a label or trade mark on packages of Tobacco; and I do hereby declare that the said invention is represented in the accompanying drawings, making part of this specification.

I do not claim the use of the reading matter here exhibited but propose to vary the same as occasion may require or dispense with reading matter entirely. The invention relates to the picture only, which picture may be used either with or without any suitable reading matter.

Having thus described my invention, what I claim as new and desire to secure by Letters Patent is.

The design herein represented, as a trade, mark or label for packages of Tobacco.

In testimony of which invention I hereunto set, my hand.
